Specification for Design.

Patented Apr. 14, 1914.

Application filed September 5, 1913. Serial No. 788,357. Term of patent 14 years.

To all whom it may concern:

Be it known that I, Victor GUINZBURG, a citizen of the United States, and a resident of the city, county, and State of New York, and whose post-office address is 725 Broadway, in said city, have invented a new, original, and ornamental Design for a Protective Shield, of which the following is a specification.

Reference is to be had to the accompanying drawing, in which:

Figure 1 is a front elevation of the pro-

tective shield, showing my design, Fig. 2 is a rear elevation of the same, and Fig. 3 is a perspective view of the same.

I claim:

The ornamental design for a protective shield as shown.

Signed at the city, county and State of New York, this 2 day of September, 1913.

VICTOR GUINZBURG.
